UNITED STATES PATENT OFFICE.

NEWELL M. BOYNTON, OF BRATTLEBOROUGH, VERMONT, ASSIGNOR TO THE
E. P. CARPENTER COMPANY, OF SAME PLACE.

ORGAN STOP-ACTION.

SPECIFICATION forming part of Letters Patent No. 443,426, dated December 23, 1890.

Application filed September 22, 1890. Serial No. 365,702. (No model.)

To all whom it may concern:

Be it known that I, NEWELL M. BOYNTON, a citizen of the United States, residing at Brattleborough, in the county of Windham 5 and State of Vermont, have invented a new and useful Improvement in Organ-Actions, of which the following, together with the accompanying drawings, is a specification sufficiently full, clear, and exact to enable persons skilled in the art to which this invention appertains to make and use the same.

My present invention relates to the construction and organization of the stop mechanism in reed-organs and to the devices for connecting and operating the stops or mutes and other parts; and it consists in certain improvements, such as described, the object of my invention being to facilitate convenience and economy in manufacture and to afford a practically efficient and durable action that will operate with smooth and easy movement, the particular subject-matter claimed being hereinafter definitely specified.

In the drawings, Figure 1 is a plan or horizontal section at line xx , Fig. 2, showing such parts of a reed-organ as will illustrate my invention. Fig. 2 is a vertical transverse section of the organ-action at line yy , Fig. 1. Fig. 3 is a back view, and Fig. 4 is a front 30 view with parts of the frame in section.

Referring to parts, A denotes the sound-board or top of the wind-chest, having the cell-board A' fixed thereon for containing the reeds and with the swell or top boards a , a' and partitions a^2 disposed in connection therewith, as shown.

B indicates the key-frame, B' the manual keys, C the tracker-pins, and C' the valve that controls the wind-passages through the reed-cells, all of which parts can be of the usual well-known construction, and need not therefore be herein more fully described.

D and D' indicate the mutes hinged to the cell-board for stopping off the different sets of reeds or sounding devices in the usual manner. The back mute D' has a projecting pin or stud d' , and the front mute has a strap d , and the operating mechanisms are connected with said stud and strap for opening and clos-

ing the respective mutes, as will be herein-after explained.

E indicates the octave-coupler, consisting of a series of rocker-levers e , of well-known form, (only one of which is here shown), fulcrumed upon the hinged board or supporter, 55 to be brought into action in the usual manner by elevation of the forward edge of said supporter.

F F indicate wire rock-shafts which are disposed transversely in relation to the action 60 beneath the top boards a , a' , as indicated, their rear ends respectively bent into the form of a crank f , adapted to connect with the actuating mechanism, while their front ends are bent laterally at a right angle, or 65 nearly so, as shown. The end of one shaft F is provided with a hook or offset f' , that connects with the strap d of the mute D, and the end of the other shaft F is formed into the peculiarly-shaped lifter-arm or upwardly-70 arched portion F^2 , disposed beneath the coupler-board E to swing in a plane substantially perpendicular to the shaft and parallel with the edge of the coupler-board. The top board a is slotted to accommodate the lifter 75 end F^2 , which when elevated by the rocking of the shaft F raises the coupler into its operating position. The front mute D is lifted and depressed by the rocking action of the shaft F.

A series of tilting levers H are provided at the rear part of the action and centrally fulcrumed upon the bar H' in the manner shown. The rear end of each of said tilting levers H is furnished with a circular disk or wheel h , 85 pivoted or journaled in the bifurcated end of the lever in a manner to rotate freely, while the front ends of said levers are respectively connected by suitable links I to the mute D', the front-mute-actuating shaft, and the coupler-adjusting shaft F. The connecting-link I is made of wire, with one of its ends passed through the end of the tilting lever H and bent as a hook, while its other end is bent in the form of a ring and embraces the crank f , 90 said ring being lined with a loop of felt or cloth, as at i . The felt i is held in position by the ring being closed down upon the ex-

tended ends of the felt, (see Figs. 2 and 3,) forming a simple and efficient joint that works easily and without noise.

- J indicates a cranked-wire lever fulcrumed, 5 as at *j*, on the brace or back-board K, which is recessed and grooved for the reception thereof. Said lever has at its lower end a lateral bend or offset *J'*, disposed in position for contact with the wheel *h* of the tilting lever, while the upper arm of said lever J has a lateral bend or offset *J²*, that passes through or engages with the pull-bar or stop M. A series of these swinging levers, corresponding in number with the tilting levers 10 II, and stop-pulls are employed. The pull-bars are of usual form and are arranged in the name-board L in well-known manner. When the stop-rod M is drawn out, the lever J is caused to swing, and its laterally-offset 15 lower end *J'* moves backward in a positive line, passing into contact with the wheel *h*, thereby effecting the depression of the rear end and elevation of the front end of the tilting lever II by the wheel *h* rolling beneath 20 the end *J'*, the action being smooth and easily effected by reason of the free rotation of said wheel. The front end of the tilting lever II being thus elevated draws up the link or connecting-rod I, in the case of the first lever II 25 raising the mute D', and in case of the second lever II causing partial rotation of the shaft F by lifting its crank *f*, so that the cranked front end *f'* of said shaft will raise the front mute D, and in the case of the third lever II 30 rocking the shaft F, so that its laterally-offset curved end *F²* will press upward the board E and put the octave-coupler into position for engagement with the buttons *b* of the keys and the flanges *c* of the tracker-pins C. 35
- In the present instance I have shown only three stops, that number being sufficient to illustrate the construction of the mechanism; but it will be understood that in practice any desired number of stops may be used in a single organ, the individual stop mechanisms 40 consisting of the pull-bars M, swing-lever J, tilting lever II, with wheel *h*, and connections from said levers being as herein illustrated and described, the back mutes D having connections direct from the ends of the tilting lever II, while the front mutes D and the octave-coupler E are provided with transversely-disposed rocker-shafts, as F F, with cranked ends *f* to receive the connecting-links at the 45 front ends of the tilting levers.
- P indicates a horizontal shaft, expression-roll, or rocker-bar extending longitudinally of the action and disposed adjacent to the front ends of the tilting levers II. Said shaft 50 is provided with pins or fingers *n*, which project backward under the ends of the levers II, and by means of which all of the series of levers II can be simultaneously elevated by a partial rotation of the shaft P. This shaft P 55 constitutes the full organ or knee stop, and is journaled or pivoted at its ends to rock

freely, and is connected with the usual knee-operating device in any suitable or convenient manner to be actuated when desired.

I am aware that an expression roll or shaft 70 having fingers has heretofore been employed for the grand-organ stop, and therefore do not claim such device otherwise than in the combination herein shown. Neither do I claim, broadly, the use of wire swing-levers 75 fulcrumed on the brace in connection with stop-pulls, as such levers have heretofore been employed, but, so far as I am aware, in different construction and combination from that herein set forth.

I claim as my invention, to be herein secured by Letters Patent—

1. The combination, substantially as described, of the tilting lever II, fulcrumed at II' and provided with a wheel *h*, pivoted in 85 its bifurcated rear end, the stop-pull M, the swinging lever J, formed, as shown, with the central hinging part *j*, whereby it is fulcrumed on the brace K, the laterally-offset lower end *J'*, disposed for engaging said wheel *h* below 90 the fulcrum, the laterally-offset top end *J²*, engaging with the pull above the fulcrum, the connecting-link I, and the mute D', for the purposes set forth.

2. The combination, substantially as described, of the tilting lever II, fulcrumed at II' and having the wheel *h* mounted on its rear end, the transversely-disposed rocker-shaft F, having the laterally-offset lifter end *f'* and the crank-arm *f*, the link I, connecting said crank-arm with the forward end of said tilting lever, the swing-lever J, fulcrumed on the brace K and having an offset lower end that engages the wheel *h*, and the pull-bar M, connected with the top arm of said 105 lever, for the purposes set forth.

3. The transversely-disposed shaft F, having the crank *f* and laterally-offset curved end *F²*, in combination with the octave-coupler E, the link I, the tilting lever II, the swing-lever J, and the pull-bar M, all disposed for operation substantially as shown and described.

4. The combination, substantially as described, of the stop-pulls M, the swing-levers J, fulcrumed on the back piece K and having the offset ends *J²* and *J'*, the tilting levers II, having the wheel *h* pivoted in the bifurcated rear end thereof, the connecting-links I, carrying the felt-supporting ring *i*, the cranked rock-shafts F F, the mutes D D', octave-coupler E, and expression-roll P, having fingers *n*, that extend beneath the ends of said tilting levers, all disposed as shown, and for the purposes set forth.

Witness my hand this 18th day of September, A. D. 1890.

NEWELL M. BOYNTON.
